Orra A. Ostrander

BY
J. N. Gilbert
ATTORNEY

UNITED STATES PATENT OFFICE.

ORRA A. OSTRANDER, OF KIRKWOOD, NEW YORK.

TAIL HOLDER FOR CATTLE.

Application filed October 7, 1921. Serial No. 506,132.

To all whom it may concern:

Be it known that I, ORRA A. OSTRANDER, a citizen of the United States, residing at Kirkwood, in the county of Broome and 5 State of New York, have invented certain new and useful Improvements in Tail Holders for Cattle, of which the following is a specification.

My invention relates to an improvement 10 for tail holders for cattle, and for holding the tails of cows while being milked, and which may be readily operated, and attached and removed, and easily manufactured, and it has for its object to provide a light easily manufactured device which 15 will not annoy the animal by attachment of the same, by reason of pressure and which will not injure the body of the animal, and can be manufactured at low cost for the 20 purposes specified. To further aid in these purposes, and objects, my device is constructed of wire, so as to preserve lightness as well as strength. With these objects in view my invention consists in certain novel 25 features of construction and arrangement of parts as will be hereinafter more fully described and pointed out in the claim, referring had to the accompanying drawings, in which—

30 Fig. 1 is a view of my device in perspective as applied to an animal.

Fig. 2 is a plan view of my device.

Fig. 3 is a side view of my device.

35 Fig. 4 is a plan view of a detailed part of my device.

Fig. 5 is a plan view of a detailed part of my device.

Fig. 6 is a side view of detailed part of my device.

40 Fig. 7 is a side view of a detailed part of my device.

Fig. 8 is a view of my device in perspective.

45 The same reference characters denote like parts in each of the several figures of the drawings.

In carrying out my invention, I employ 50 the opposing jaws A, A' and B and B', the jaws A and A' preferably constructed of wire have the handle portions 2, 2 and 3, 3 extending from the jaws and bent around the axis 4. The jaws B and B' preferably formed of wire are also bent around the axis 4 and pivot thereon and extend at an 55 angle to the handle portions 2, 2 and 3, 3. The base of the jaw 4 is formed by the bent

arms y, y which are extended around the axis 4 thus forming a double armed member, while the jaw B' consists of a single extension of wire, the base of which is bent 60 around the axis 4 and thus hinged thereto, and meets in its opposite end, the bend in the jaw B; in one form of my device, I have slidably mounted on the arms of the jaws, A, and A' the plate C shown in Fig. 65 5 having the openings therein, 5, 5, 5, 5 each adapted to receive one of the wire arms, 2, 2 and 3, 3 projected in formation from the jaws A and A'; also I have slidably mounted on the arms of jaws B and B' 70 the plate D having the openings therein, 6, 6, 6 as shown in Fig. 4; and each adapted to receive one of the wire arms y, y and B' projected in formation from the jaws B and B'. In one form of my invention, I have 75 mounted on the respective arms extended from jaws A, and A' the loop bar E having formed therein the loops 8, 8, 8, 8 adapted to slidably receive one of the arms projected in formation from the jaws A and A'; 80 also I have mounted on the respective arms extended from the jaws B and B' the bar F and having formed therein the loops 9, 9, 9 each adapted to slidably receive one of the arms projected in the formation from 85 the jaws B and B'; the outer end of the arms 2, 2 and 3, 3 are turned to form a shank at 7, preventing the guard or sleeve C or the bar E from sliding off from the arms; mounted in any convenient manner 90 on the interior or inner side of the jaws A and A' I have the leather lining strips, 10 and 10; forming a yielding face for contact with the leg of the animal. In the 95 operation of my device, I move the plates C and D or the bars E and F along the arms towards the axis 4 so as to permit of a wider movement of the arms or opening of the jaws A and A' and B and B'; and I place the curved portions of jaws A and A' 100 over the gambrel portion of the hind leg and place the bushy part of the tail between the arms or jaws B and B'; I then slide up the plates C on the arms of the jaws A and A'; and the plate D on the arms of the jaws B and B' until the jaws A and A' are held in firm grasp of the cord of the leg, and the jaws B and B' hold the bushy part of the tail securely in their grasp. The arms or jaws B and B' gripping the tail prevent 105 the same being switched or moved. When I have finished milking I open the jaw

members A and A' and B and B' and remove the holder from the tail and leg; by sliding back the slide plates C and D or the bars E and F; towards the axis 4 of the jaws; thus loosening the grip.

Having thus described my invention, what I claim as new and for which I desire Letters Patent is as follows:

In a device of the class described comprising two pairs of hinged wire jaws, both pairs hinged on the same axis, both of wire, said jaws terminating at one end in a curved formation, the one for engagement with the hind leg of a cow and the other for engaging the bushy part of the tail, arms project-

ing backward from each jaw member, plates having openings therein, for the passage of the projecting arms therethrough, and being slidably mounted thereon, and adapted to be moved forward toward the pivot point 20 of the jaws and thereby permitting their opening, and moved backward from the pivot point of the jaws, and thereby bringing together the curved portions of the jaws, and holding the same in firm engagement 25 with, the leg and tail of the cow respectively.

In testimony whereof I affix my signature.

ORRA A. OSTRANDER.
